UNITED STATES PATENT OFFICE.

RANEY J. ROBERTS, OF DETROIT, MICHIGAN.

WATER-HEATER.

1,315,988.

Specification of Letters Patent. Patented Sept. 16, 1919.

Application filed December 11, 1918. Serial No. 266,207.

To all whom it may concern:

Be it known that I, RANEY J. ROBERTS, a citizen of the United States, residing at Detroit, county of Wayne, State of Michigan, have invented a certain new and useful Improvement in Water-Heaters, and declare the following to be a full, clear, and exact description of the same, such as will enable others skilled in the art to which it pertains to make and use the same, reference being had to the accompanying drawings, which form a part of this specification.

This invention relates to water heaters, and its object is to provide a simple and efficient construction for the heating of a body of water in a container, provision being made whereby a portion of said body is heated more rapidly than the main body, enabling hot water to be drawn from the receptacle before the entire body has become fully heated. A further object of the invention is to provide a construction including a tubular member in which steam is produced by the burner and ejected into the main body of water in the receptacle, and further novel features are involved in the construction of a portion of the receptacle providing a pocket over the burner and the provision of a false bottom separating the lower part of the receptacle from the upper part, provision being made for a restricted flow from one part of the receptacle into the other under the influence of heat, the flow being forced by the ejection of steam through the false bottom into the main body of water in the receptacle. These objects and novel features of the invention are hereinafter more fully described and illustrated in the drawings—

40 Figure 1 is a vertical section of a water heater embodying my invention.

Fig. 2 is a vertical section taken on the line $y-y$ of Fig. 1.

Fig. 3 is a cross section taken on line $x-x$ of Fig. 2.

The heater may be made in various forms for various uses, either as a heater of water for general purposes or as a water heater for portable bath tubs as shown in pending application Serial No. 263,653, filed November 22, 1918. The receptacle 1, in the construction here shown, is provided with a cover 2 through which water may be introduced into the receptacle, but water may be supplied thereto in any approved manner. An essential characteristic of the receptacle is in the

provision of a false bottom 3 spaced some little distance above the bottom 4 segregating about one-fourth the volume of the receptacle from the main body thereof. This 60 false bottom as is shown in Figs. 2 and 3, is provided with two apertures 5 and 6 upon opposite sides to allow for restricted circulation of water between the upper and lower sections of the receptacle. The main bottom 4 of the device is convex at the center as indicated at 7 providing a cavity or pocket 8 on the lower side directly above the burner indicated at 9. This burner may be supplied with fuel through a pipe 10 70 connected with any convenient source of supply (not here shown). The convex portion 7 is apertured at the uppermost point, and a tube 11 is connected therewith leading upward through the false bottom 3 and 75 opening through the side of the receptacle as indicated at 12 providing a passageway for air from the upper side of the pocket to the atmosphere. By this arrangement, which provides a vent for the pocket 8, the 80 flame from the burner impinges against the entire surface of the pocket, and without provision of a vent a dead air space would be formed preventing the full effect of the heat being transferred to the water in the 85 tank. This tube 11 becomes heated by the passage of heated air and gas therethrough and assists in heating the body of water in the receptacle.

A **U** shaped tube 13 is provided in the 90 bottom 4 as indicated particularly in Fig. 3 having one leg 14 shorter than the other leg 15. The leg 15 terminates just below the aperture 6 in the false bottom and the leg 14 terminates a greater distance below the 95 aperture 5, and this tube passes through the pocket 8 as indicated and is directly subjected to the flame of the burner. The tube being open at each end is filled with water which is thus pocketed directly over the 100 burner and rapidly passes into steam which flows out through the leg 15. As this leg terminates slightly below the aperture 6, steam passing therethrough picks up water from the lower chamber 16 between the two 105 bottoms 3 and 4 and forces it into the upper chamber 17 and thus assists in circulation between the two chambers. These apertures 5 and 6 are not very large and prevent a free circulation of water between the two 110 chambers resulting in the heating of the water in the chamber 16 before the water in

the chamber 17 has become materially heated. The purpose of this is to enable water to be drawn off through the valve 18 without having to wait until the entire body of water has become heated. By making the tube member 13 with one leg shorter than the other, a siphoning effect takes place. The steam blowing out of one end draws water into the other and a more rapid circulation is thus provided for and the entire body of water is heated by the projection of steam into the larger body which is out of contact with the wall of the vessel directly heated by the burner. Without the use of the tube 10 the entire body of water becomes heated only by contact with the lower wall 4 of the receptacle. In the arrangement shown, not only does the water become heated by reason of contact with this lower wall but the steam produced in the tube is ejected into the body of water out of contact with the wall and the entire mass of water is heated more rapidly than would otherwise be the case resulting in an efficiency of operation which is one of 15 the objects attained by the construction shown.

By use of the pocket described for the flame, the heat from the burner is localized, resulting in a more intense heat at a point 20 of the bottom and causing a more rapid circulation within the lower chamber 16 than would be the case if the heat were dispensed equally over the whole bottom and, by this arrangement and the use of the tube 13, the 25 heat is not only localized as stated, but provides a space of intense heat through which the tube passes and the venting of the pocket prevents the spreading of the flame.

Having thus fully described my invention, 30 what I claim is—

1. A water heater comprising a receptacle, an apertured wall therein dividing the receptacle into an upper major and a lower minor compartment, a burner beneath the 35 bottom of the lower compartment, and a U shaped tube, the legs of the U extending upward into the lower minor compartment

and the connecting portion between the legs extending through the bottom of the compartment across the burner, one leg of the 50 tube being greater in length than the other, and a discharge valve for the said minor compartment.

2. In a water heater, a receptacle having the bottom wall thereof centrally convexed, 55 a burner beneath the convex portion, a tube extending upward through the receptacle to the atmosphere providing a vent for the pocket formed by the convex portion, and a U shaped tube, the legs of which extend upward into the compartment and the connecting portion of which extends beneath the 60 bottom across the burner.

3. A water heater comprising a receptacle, a false bottom formed therein having two 65 apertures on opposite sides of the center, the bottom of the receptacle having a convex portion, a burner therebeneath, a tube extending from the top of the convex portion through the false bottom leading to the atmosphere at the side of the receptacle, a U shaped tube, the legs of which extend 70 through the bottom of the receptacle terminating beneath the false bottom, the open 75 ends respectively of the tube being in alignment with the apertures in the false bottom, one leg of the tube being of greater length than the other and the cross member of the U passing through the bottom and across the burner, and a discharge valve for the compartment below said false bottom.

4. A water heater comprising a receptacle having a convex bottom, a burner therebeneath, a tube providing a vent for the said convex portion leading upward through the 85 receptacle to the atmosphere, and a U shaped tube, the closed portion of the U extending across the convex portion beneath the bottom and over the burner and the legs thereof 90 extending into the receptacle, one of the said legs being of greater length than the other.

In testimony whereof I sign this specification.

RANEY J. ROBERTS.
